(57) **CLAIM**

The ornamental design for an orthotic sandal as shown and described.

DESCRIPTION

FIG. 1 is a side perspective view of an orthotic sandal showing the new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof;

FIG. 7 is a rear elevation view thereof; and,

FIG. 8 is a cross-sectional view thereof, taken along line 8-8 of FIG. 4.

The broken lines of the drawing depict non-claimed portions of the orthotic sandal and form no part of the claimed design.
